UNITED STATES PATENT OFFICE.

JEAN JULES MARIE ANTOINE EUGÈNE SCHNEIDER, OF PARIS, FRANCE.

SHOCK-ABSORBING APPARATUS FOR LANDING-CARRIAGES OF AEROPLANES.

1,332,764.

Specification of Letters Patent.

Patented Mar. 2, 1920.

Application filed July 2, 1919. Serial No. 308,267.

To all whom it may concern:

Be it known that I, JEAN JULES MARIE ANTOINE EUGÈNE SCHNEIDER, a resident of Paris, in the Republic of France, have invented a new and useful Improved Shock-Absorbing Apparatus for Landing-Carriages of Aeroplanes, which invention is fully set forth in the following specification.

The shock-absorbers for the landing carriages of aeroplanes have hitherto consisted of rubber bands by means of which the axle of the landing wheels is fastened on a cross-piece carried by a frame projecting from underneath the car or fuselage of the aeroplane.

Shock-absorbers of that kind are constituted by a continuous band, the two ends of which are attached to the crosspiece supporting the landing axle, after having wound the said band a very large number of times alternately over the axle and under the said crosspiece.

That arrangement constitutes a sort of elastic binding or ligature, and the elasticity of the said ligature is relied upon to allow the aeroplane to execute a downward movement relatively to the landing axle at the time of landing.

That known arrangement has many drawbacks. First, the elasticity of the ligature is necessarily very limited. The elongation of the band occurs almost exclusively at its ends, that is to say, close to its points of attachment to the crosspiece. Moreover, it is necessary to give an initial tension to the band when winding it around the landing axle, and this renders the placing of the band in position very laborious, while as a consequence it is impossible to determine the extension, or more exactly the range of movement between the landing carriage and the aeroplane which is still available at the instant when the landing wheels come into contact with the ground.

The present invention has for its object to provide an improved shock-absorbing apparatus employing bands or cables of rubber or the like, but having none of the drawbacks above referred to.

According to the present invention, the elastic band between the landing carriage axle and the frame fixed to the car or fuselage of the aeroplane, is constituted by a large number of separate elastic elements for which points of attachment are provided on

one hand upon supports carried by or fixed to the said axle, and on the other hand upon ribs or other projections of a crosspiece forming part of the frame. These band elements, the number and length of which may be varied as desired, are preferably divided into groups according to a plurality of planes at right angles to the landing axle. It will of course be understood that by making the supports and the attachment ribs of sufficient length, it is possible to arrange a very large number of bands in one and the same plane.

Each band at the time of landing will be able to become elongated independently of the others, and the relatively short elements of the total band will all or almost all cooperate to moderate the shock. The elements of the fractionated elastic band may be mounted without initial tension, because the improved shock-absorbing apparatus comprises according to this invention, a tensioning means which allows of giving to them the initial tension after the mounting, and of regulating said tension according to requirements.

In addition to these advantages the improved shock-absorbing apparatus has another extremely important advantage, namely, one or more elements of the band can break without the shock-absorbing apparatus being thereby rendered useless, whereas in ordinary shock-absorbers the band may break and such breakage may not be visible at the time of examination or inspection of the apparatus, while the band when broken must be replaced as a whole, which necessitates, in addition to the cost, an amount of work which is at least much greater than the work required for replacing one or more separate elements.

Several practical constructional forms of this invention are illustrated by way of example in the accompanying drawings in which:

Figure 1 illustrates a first constructional form, partly in side elevation and partly in longitudinal section along the longitudinal center line of the landing carriage.

Fig. 2 is a cross section on the line II—II of Fig. 1.

Fig. 3 is partly a side elevation and partly a section on the line III—III of Fig. 1, of the middle portion of the landing axle to which are fastened the supports for the

attachment of the separate elastic elements of the shock-absorbing apparatus.

Fig. 3^a is a cross section similar to Fig. 2 of a first modification.

5 Figs. 4, 5 and 6 illustrate a second modification.

Fig. 4 is a side elevation partly in section along the longitudinal center line of the landing carriage.

10 Fig. 5 is a corresponding plan.

Fig. 6 is a cross section on the line VI—VI of Fig. 4.

Fig. 7 is a diagrammatic elevation of another modification.

15 Figs. 8 and 9 are respectively diagrammatic longitudinal and end elevations of another modification.

Figs. 10 and 11 show respectively a cross-section and a side elevation of another modification.

20 In these various figures, A is the axle of the landing carriage carrying at its end the landing wheels B. C is the frame carried by the car or fuselage of the aeroplane; to this frame is attached the girder D that is connected elastically to the landing axle.

According to this invention the axle A is provided with a series of supports E to which are attached at their similar ends a 30 series of elastic bands, the other ends of which are attached to parts carried by corresponding ribs F formed or fixed on the girder D.

In the constructional examples shown, 35 the supports E consist of simple metal plates of suitable length slipped upon the landing axle directly or through the medium of a sleeve G (Fig. 3). These metal plates are assembled and secured between collars a 40 (formed or fixed on the landing axle) by bolts e extending through said plates and collars and also through the spacing rings H interposed between the plates.

The ribs F may be composed of metal 45 plates fixed or welded to the girder D; they may, as shown in Fig. 3, be formed on a casting fixed to the said girder.

The elastic band between the landing carriage axle and the frame C comprises a series 50 of rubber elements I corresponding in number to the points of attachment provided on the supports E and the ribs F. Since the supports E, as shown in the drawing, are arranged preferably at right angles to the axis

55 of the landing axle, the points of attachment of the bands I may be grouped along lines parallel to the said axle and provided on a series of rods or long bolts J extending through holes formed in the said supports.

60 Upon these rods are mounted thimbles or grooved pulleys K. The lower points of attachment instead of being situated directly upon the ribs F, may likewise be provided on long bolts L extending through the said 65 ribs and supported by the latter, these bolts,

like the bolts J, being fitted with thimbles or grooved pulleys M.

Each separate band I consists of a rubber cable the ends of which are wound on the corresponding thimbles K—M, and then 70 fixed by binding to the body of the cable. In the example shown, the total elastic band is composed of eight rows of bands each comprising twelve elements. These bands are preferably set in place without initial 75 tension, and the initial tension which is adjustable at will, can be given to them by means of a screwjack serving as a tensioning device, such as the one shown in Figs. 1 and 4. One of the elements of this screwjack, 80 namely, the nut N, is situated immediately below with the landing axle A which rests upon it through the medium of rubber pads n. The other element of the screwjack, namely the screw O, is adapted to rotate in 85 a footstep bearing P fixed on the girder D.

The nut N is held and guided in such a manner as to prevent it from rotating. This may for instance be effected by two sheet metal uprights N¹ fixed on the girder D 90 between which the facets of a square or rectangular nut are held against rotation and are adapted to slide.

On turning the screw O by means of a key formed by a pin engaged in a hole o 95 in the said screw, the screw can be lowered by causing the nut to take a bearing against the underside of the landing axle. By this means the bands I are tensioned in the direction of the arrows (Fig. 1).

It will be readily understood that in the case of a landing, the girder D having a tendency to move toward the ground, all the bands I will have a tendency to stretch and can in effect become stretched to absorb 105 the shock of the landing.

Should any one of the bands break, it will be readily apparent on inspection of the apparatus and the broken band can be rapidly and cheaply replaced.

It is preferred to cover the whole of the supports E by metal plate E¹.

The entire shock-absorbing device constructed as above described, may be made very long and yet accommodated in a relatively narrow space without any projection above the landing axle; it is preferably enclosed in a casing Q of fuselage form.

In the modification illustrated in Fig. 3^a, the girder D connected to the frame C has a narrow width, or more strictly speaking, its vertical longitudinal faces are situated close to the vertical longitudinal symmetry plane of the landing carriage. The plates E are arranged in groups on both sides of the 120 girder. The girder comprises a bottom sole-plate D¹ attached to outer gusset plates D² projecting from which are the ribs F in line with the plates E.

As in the modification shown in Figs. 4, 130

5 and 6, the attachment ribs F may be formed directly on the bottom of a casing Q of fuselage shape, which constitutes of itself in such a case the girder fixed to the 5 frame C.

It is to be understood that it is not absolutely indispensable to divide the bands into such a large number of elements as in the example shown in Figs. 1 to 3. Fig. 4 illustrates a modification in which each band element consists of a cable wound in V-shape, the middle of the cable being guided around an upper or lower thimble, while its ends are bound after passing around two 15 lower or upper thimbles.

Fig. 7 is a diagrammatic elevation of another modification in which a determined number of band elements I are fixed to one another transversely instead of longitudinally. 20

Shortly described, the number of band elements and their distribution between the supports fixed to the landing axle and the 25 points of attachment fixed to the girder carried by the frame, may be varied at will.

Figs. 8 and 9 illustrate in diagram (respectively in longitudinal and end elevation) a modification in which each of the supports E carried by the axle A is formed on its 30 upper edge with a suitable number of notches R in each of which there engages the loop of a band I whose ends are attached for instance to hooks f of two lower attachment ribs F.

35 In the modifications illustrated in Figs. 10 and 11, respectively in cross section and in side elevation, a landing axle A of suitable section serves as an attachment for a series of supports E arranged in a number 40 of transverse planes, and each consisting of a hook to which there is hooked a block I¹ serving as an attachment for one of the ends of a bundle of bands I attached at their lower ends to a block I² hooked in its 45 turn to an attachment rib F of the girder D. An initial tension can be given to each bundle of bands by means of a nut S screwing on a screw-threaded end of the supporting hook E, and bearing upon the axle A.

50 What I claim is:

1. A shock-absorbing apparatus for the landing carriage of an aeroplane comprising a girder fixed to the frame of the carriage, a wheeled axle extending through the 55 girder, a support mounted on the axle to receive the upward thrust of the same, a plurality of elastic elements connecting the support with the lower part of the girder to absorb the landing shock imparted to the 60 wheeled axle, and a casing of fuselage form inclosing the girder and associated members.

2. A shock-absorbing apparatus for the landing carriage of an aeroplane comprising 65 a girder fixed to the frame of the carriage,

a wheeled axle extending through the girder, a support mounted on the axle to receive the upward thrust of the same, a plurality of elastic elements connecting the support with the lower part of the girder to 70 absorb the landing shock imparted to the wheeled axle, and means operative to force apart the girder and support to tension initially the elastic elements.

3. A shock-absorbing apparatus for the 75 landing carriage of an aeroplane comprising a girder fixed to the frame of the carriage, a wheeled axle extending through the girder, a series of parallel plates journaled on the axle to receive the upward thrust of 80 the same, and a group of elastic elements connecting each of the plates with the lower part of the girder, the several groups of elastic members operating to absorb the landing shock imparted to the wheeled axle. 85

4. A shock-absorbing apparatus for the landing carriage of an aeroplane comprising a girder fixed to the frame of the carriage, a wheeled axle extending through the 90 girder, a series of parallel plates journaled on the axle to receive the upward thrust of the same, a group of elastic elements connecting each of the plates with the lower part of the girder, the several groups of elastic members operating to absorb the 95 landing shock imparted to the wheeled axle, and means operative to force apart the girder and series of plates to tension initially the elastic elements.

5. A shock-absorbing apparatus for the 100 landing carriage of an aeroplane comprising a girder fixed to the frame of the carriage, a series of parallel ribs extending longitudinally of the lower part of the girder, a series of parallel plates corresponding to 105 said ribs journaled on the axle to receive the upward thrust of the same, and a group of elastic elements connecting each of said plates with its corresponding rib, the several groups of elastic members operating to absorb the landing shock imparted to the 110 wheeled axle.

6. A shock-absorbing apparatus for the landing carriage of an aeroplane comprising a girder fixed to the frame of the carriage, a series of parallel ribs extending longitudinally of the lower part of the girder, a series of parallel plates corresponding to 115 said ribs journaled on the axle to receive the upward thrust of the same, a lower set of parallel rods extending through said ribs, an upper set of parallel rods extending through said plates, and a plurality of elastic elements having their ends looped around the opposite sets of rods to connect elastically the plates and ribs, said elastic members operating to absorb the landing shock 120 imparted to the wheeled axle. 125

7. A shock-absorbing apparatus for the landing carriage of an aeroplane comprising 130

- ing a girder fixed to the frame of the same, a wheeled axle, and elastic elements connecting the axle and girder, said elements being arranged in sets with the members of each set provided with common means of attachment to the girder and to the axle, the several sets of elastic elements operating to absorb the landing shock imparted to the wheeled axle.
- 10 8. A shock-absorbing apparatus for the landing carriage of an aeroplane comprising a girder fixed to the frame of the same, a wheeled axle, elastic elements connecting the axle and girder, said elements being arranged in sets with the members of each set

provided with common means of attachment to the girder and to the axle, the several sets of elastic elements operating to absorb the landing shock imparted to the wheeled axle, and means operative to force 20 apart the girder and wheeled axle to tension initially the elastic elements.

In testimony whereof I have signed this specification.

JEAN JULES MARIE ANTOINE
EUGÈNE SCHNEIDER.
